SCAFFOLD LADDER

Reinhold A. Uecker, Ingar G. Rambo, and David
E. Beatty, Wauwatosa, Wis.

Application September 19, 1938, Serial No. 230,648

11 Claims. (Cl. 228—45)

This invention relates to scaffolds and more particularly to a ladder for use on scaffolds.

One object of the present invention is to produce a ladder for use on scaffolds which will be more economical to manufacture than those now on the market.

Another object is to produce a sectional ladder for use on scaffolds in which the danger from failure is reduced through suitably interconnecting the sections.

A further object is to produce a ladder having an improved locking device.

Other objects will be apparent from the following description.

In the drawings:

Fig. 1 is a side elevational view of a scaffold showing a ladder thereon embodying the present invention;

Fig. 2 is a cross-section on the line 2—2 of Fig. 1, looking in the direction of the arrows;

Fig. 3 is a cross-section on the line 3—3 of Fig. 2, looking in the direction of the arrows; and

Fig. 4 is a perspective view of the ladder.

Referring to the drawings in which like numerals indicate like parts throughout the several views, the scaffold is shown as composed of a plurality of end frames 10 superimposed on each other with the superposed frames being joined by coupling pins 11. The frames 10 are connected to other frames in the same level by cross braces 12, which are joined to the end frames by bolts and wing nuts (not shown).

Each end frame is composed of two parallel vertical posts 13, one of which is shown, which are held in spaced parallel relationship by horizontal braces 14—14.

All the above structure is, in itself, old, and is more fully described in the United States patent to Reinhold A. Uecker, No. 2,043,498, issued June 9, 1936.

The ladder, forming the subject matter of the present invention, is made in sections of the same length as the height of a scaffold end frame.

The ladder sections are supported from the upper horizontal brace 14 by a bracket 20 which is engageable around the post 13 and has a hook portion 21 engageable over the horizontal brace 14. A rung 23 is attached to the bracket 20 so as to extend at right angles to the plane of the end frames 10.

Side bars 25 are fixed on the opposite ends of the rung 23 so as to be parallel to each other and to the post 13. The side bars are preferably

made tubular and are provided with pins 26 at the upper ends which are engaged by the lower ends of the tubular side bars of the superposed ladder to insure the side bars remaining in true alignment and to provide an extra safety factor in the event of a failure of the bracket 20. The side bars 25 support a plurality of rungs 27, 28, 29 parallel to the rung 23, the rungs 27, 28, 29 being fixed, preferably by welding, between the side bars 25.

A second bracket 30 is carried by the rung 28, and is engageable around the post 13. An inverted U-shaped yoke 31 is formed on the inner end of the bracket 30 and extends at right angles to the body of the bracket, or parallel to the rungs 23 and 28. A second yoke 32, parallel to and in alignment with the yoke 31 is formed on the opposite side of the bracket from the yoke 31. A latch 33 is pivotally mounted in the yoke 31 and engages in the yoke 32, and acts both as a latch and as a supplemental support for the ladder in the event of a failure of the bracket 20.

In order to strengthen the ladder and to fix the brackets more securely on the rungs, braces 34 and 35 are provided for the brackets 20 and 30 respectively. The braces 34 and 35 are closely adjacent the rungs 23 and 28 respectively, and are secured to both the brackets 20 and 30 and to both side bars 25.

Having thus described the invention it is realized that it is susceptible to various changes and modifications and it is not, therefore, desired to limit the invention to the precise form herein shown and described, but only by the scope of the appended claims.

The invention is hereby claimed as follows:

1. A ladder for use with a scaffold or the like having a vertical post and a horizontal brace, said ladder comprising, an attaching bracket engageable around said post and supported on said brace, a rung attached to said supporting bracket, a side bar connected to each end of said rung, a brace joining the lower portion of said bracket with the side bars, and a plurality of rungs carried by said side bars.

2. A sectional ladder for use with a sectional scaffold or the like having a vertical post and a horizontal brace connected thereto, said ladder comprising, a bracket engageable around said post and supported on said brace, a rung attached to said supporting bracket, a side bar connected to each end of said rung, a plurality of rungs carried by said side bars, and means on said side bars engageable with the side bars of

an adjacent ladder section to lock the side bars in alinement with the side bars of said last named section.

3. A sectional ladder for use with a sectional scaffold having a vertical post and a horizontal brace, said ladder comprising, a bracket engageable over said brace, a rung fixed to said bracket, a tubular side bar fixed to each end of said rung, a plurality of rungs carried by the side bars, and a connecting pin fixed in one end of said side bars engageable with the tubular side bars of an adjacent ladder section to maintain the sections against accidental disengagement.

4. A ladder for use with a scaffold having a vertical post and a horizontal brace, said ladder comprising a bracket engageable around said post, a yoke extending at right angles to said bracket, a second yoke attached to another portion of said bracket and in alinement with the first named yoke, a latch pivotally mounted in one of said yokes and engageable in the other said yoke, a rung attached to said bracket, a plurality of rungs carried by the side bars, and side bars attached to and carried by said rung.

5. A ladder for use with a scaffold or the like having a vertical post and a horizontal brace, said ladder comprising, an attaching bracket engageable around said post and supported on said brace, a rung attached to said supporting bracket, a side bar connected to each end of said rung, a brace joining the lower portion of said bracket with the side bars, a plurality of rungs carried by said side bars, a second bracket connected with one of said rungs and engageable with said post, and a latch carried by said second bracket.

6. A sectional ladder for use with a sectional scaffold or the like having a vertical post and a horizontal brace connected thereto, said ladder comprising, a bracket engageable around said post and supported on said brace, a rung attached to said supporting bracket, a side bar connected to each end of said rung, a plurality of rungs carried by said side bars, means on said side bars engageable with the side bars of an adjacent ladder section to lock the side bars in alinement with the side bars of said last named section, a second bracket connected with one of said rungs and engageable with said post, and a latch carried by said second bracket.

7. A sectional ladder for use with a sectional scaffold having a vertical post and a horizontal brace, said ladder comprising, a bracket engageable over said brace, a rung fixed to said bracket, a tubular side bar fixed to each end of said rung, a plurality of rungs fixed between said side bars, a connecting pin fixed in one end of said side bars engageable with the tubular side bars of an adjacent ladder section to maintain the sections against accidental disengagement, a second bracket connected with one of said rungs and engageable with said post, and a latch carried by said second bracket.

8. A sectional ladder for use with a sectional scaffold or the like having a vertical post and a horizontal brace connected thereto, said ladder comprising, a bracket engageable around said post and supported on said brace, a rung attached to said supporting bracket, a side bar connected to each end of said rung, a brace connected to said bracket adjacent the lower end thereof and joining said bracket with said side bars, a plurality of rungs carried by said side bars, and means on said side bars engageable with the side bars of an adjacent ladder section to lock the side bars in alinement with the side bars of an adjacent section.

9. A sectional ladder for use with a sectional scaffold having a vertical post and a horizontal brace connected therewith, said ladder comprising, a bracket engageable over said brace, a rung fixed to said bracket, a tubular side bar fixed to each end of said rung, a brace member joining the lower portion of said bracket with said tubular side bars, a plurality of rungs carried by said side bars, and a connecting pin fixed in each of said side bars engageable with the tubular side bars of an adjacent section to maintain the sections against accidental disengagement.

10. A sectional ladder for use with a sectional scaffold or the like having a vertical post and a horizontal brace connected thereto, said ladder comprising, a bracket engageable around said post and supported on said brace, a rung attached to said supporting bracket, a side bar connected to each end of said rung, a supporting brace connecting the lower end of said bracket with said side bars, a plurality of rungs carried by said side bars, means on said side bars engageable with the side bars of an adjacent ladder section to lock the side bars in alinement with the side bars of said last named section, a second bracket connected with one of said rungs and engageable with said post, and a latch carried by said second bracket.

11. A sectional ladder for use with a sectional scaffold having a vertical post and a horizontal brace, said ladder comprising, a bracket engageable over said brace, a rung fixed to said bracket, a tubular side bar fixed to each end of said rung, a supporting brace fixed to and joining the lower end of said bracket with the side bars, a plurality of rungs fixed between said side bars, a connecting pin fixed in one end of said side bars engageable with the tubular side bars of an adjacent ladder section to maintain the sections against accidental disengagement, a second bracket connected with one of said rungs and engageable with said post, and a latch carried by said second bracket.
